JAMES E. BUDD, OF BATTLE GROUND, WASHINGTON, ASSIGNEE TO M. & M. SALES & MFG. CO. INC., OF PORTLAND, OREGON

MILK-BOTTLE CAP

Application filed October 17, 1928. Serial No. 313,193.

This invention relates generally to containers for milk, and particularly to a special form of closure for milk bottles.

The first object of this invention is to provide an exceedingly simple and efficient form of closure for milk bottles, which will accomplish two purposes. First, it will prevent milk which is being poured from the bottle from coming in contact with the mouth of the bottle, which may be exposed to dust, or other foreign matter during filling, handling or vending of the bottle and contents. Second, it will prevent milk from running down the side of the bottle, which is obviously undesirable.

These, and other objects, will become more apparent from the specification following as illustrated in the accompanying drawing, in which:

20 Figure 1 is a fragmentary view of the upper portion of the milk bottle showing its mouth and the new closure member broken away in section and showing the device in a closed position. Figure 2 is similar to Figure 1, except that the bottle is being inclined for pouring and that the closure member has been set for pouring. Figure 3 is a plan of the device showing its door open. Figure 4 is a plan of the device showing its door closed. 25 Figure 5 is an enlarged section taken along the line 5—5 in Figure 4. Figure 6 is an enlarged section through a modified form of the device in which the beveled edge door is replaced by a door having a shoulder formed therein.

Similar numbers of reference refer to similar parts throughout the several views.

Referring in detail to the drawing, the device consists of a circular disk 10, preferably formed of two layers 11 and 12. In the disk 10 is formed an opening having beveled edges 13 against which can rest the edges 14 of a door 15, whose hinge 16 is formed by material in the member 12 which has not been cut away. A tab 17 is fastened on the door 15 by means of a suitable staple 18, or may be formed out of the material in the door itself, as is common practice. A wire staple 19 is placed across the side of the door frame which serves as a latch to prevent acci-

dental opening of the door, and is merely bent to one side (as shown in Figure 3) when it is desired to open the door.

In Figure 6 it will be noted that instead of having the beveled edges 13 and 14 that the disk 10—A consists of an upper portion 11—A and lower portion 12—A, both of which have a door opening formed therein, the only difference being that in the member 12—A the door opening is slightly smaller than in the member 11—A which forms a shoulder limiting the closing travel of the door.

In order that the door shall remain in the position desired as best adapted for smooth pouring of the milk, there is introduced a soft wire stay rod 20 between the members 11 and 12 and 11—A and 12—A, which holds the door in the desired position against any springing action which may exist in the hinge 16 or 16—A.

The operation of the device is as follows: After the bottle 21 is filled and capped by hand or by such machines as are now in common use and delivered to the consumer, and it is desired to remove a portion of the milk from the bottle it is only necessary to move the staple 19 slightly to one side, as shown in Figure 3, and lift upwardly on the tab 17 causing the door to open. The door is now swung back to approximately the position shown in Figure 2, and it will be found that the milk can now be easily and smoothly poured from the bottle without coming into contact with the rim 22, which might ordinarily be contaminated.

If it is desired to pour all of the milk out of the bottle it is only necessary to close the door 15, and if the bottle is to be subjected to rough handling it is well to move the staple 19 back to the position shown in Figure 4 to prevent any accidental opening of the door.

In many instances when the form shown in Figure 6 is employed the staple 19 will not be necessary.

It can readily be seen that the size of the door 15 and the exact shape illustrated in the drawing are immaterial, as these can be varied greatly without departing from the spirit of this invention.

I am aware that milk bottle caps have

long been constructed in the past, I therefore do not wish to cover such devices broadly, but I do intend to cover all such forms and modifications thereof as fall fairly within the appended claims.

I claim:

1. A milk bottle cap consisting of a circular paper disk having an opening formed through same having a closure hinged to one side of said opening, the sides adjacent to said hinge being perpendicular thereto, the remaining side consisting of two straight faces angling outwardly toward the middle of the closure, and a soft wire stay within the structure of said door and cap perpendicular to its hinge adapted to be bent as said closure is moved and to hold said door in the position to which it is moved.
2. A milk bottle cap consisting of a circular paper disk having an opening formed through same having a closure hinged to one side of said opening, the sides adjacent to said hinge being perpendicular thereto and the remaining side having its middle projecting beyond its ends, a staple in said disk adapted to be bent over the point of said closure and hold same in position, a soft wire stay within the structure of said door and cap perpendicular to its hinge adapted to be bent as said closure is moved and to hold said door in the position to which it is moved, and a tab attached to the pointed end of said door on its outer side adapted to facilitate the opening of said closure.
3. A closure for milk bottles consisting of a paper disk having an opening formed therethrough, a closure for said opening hinged to one edge thereof, a wire within said hinge perpendicular to said hinge adapted to hold said closure to any open position.
4. A closure for milk bottles consisting of a paper disk having an opening formed therethrough, a closure for said opening hinged to one edge thereof, a wire within said hinge perpendicular to said hinge adapted to hold said closure in any open position, and latch means for holding said closure in a closed position.
5. A milk bottle cap consisting of a circular paper disk having an opening formed through same having a closure hinged to one side of said opening, the sides adjacent to said hinge being perpendicular thereto and the remaining side having two obtuse faces forming a point thereon, and a staple in said disk adapted to be bent over the point of said closure and hold same in position.

JAMES E. BUDD.
